CLAIM

The ornamental design for an outer shell for a transport refrigeration system, as shown and described.

DESCRIPTION

FIG. 1 is a perspective view of an outer shell for a transport refrigeration system showing our new design;

FIG. 2 is a front elevational view of FIG. 1;

FIG. 3 is a rear elevational view of FIG. 1;

FIG. 4 is a top plan view of FIG. 1;

FIG. 5 is a left side elevational view of FIG. 1;

FIG. 6 is a right side elevational view of FIG. 1;

FIG. 7 is a front perspective view of the outer shell for a transport refrigeration system shown in an open position;

FIG. 8 is a front elevational view of FIG. 7;

FIG. 9 is a rear elevational view of FIG. 7;

FIG. 10 is a top plan view of FIG. 7;

FIG. 11 is bottom plan view of FIG. 7;

FIG. 12 is left side elevational view of FIG. 7; and,

FIG. 13 is a right side elevational view of FIG. 7.

The broken lines shown in the drawing disclosure are for illustrative purposes only and form no part of the claimed design.
